UNITED STATES PATENT OFFICE.

EMIL M. KRAMER, OF MORTON, ILLINOIS.

CARBURETER.

1,231,175.

Specification of Letters Patent. Patented June 26, 1917.

Application filed May 9, 1916. Serial No. 96,375.

To all whom it may concern:

Be it known that I, EMIL M. KRAMER, a citizen of the United States, residing at Morton, in the county of Tazewell and State of Illinois, have invented certain new and useful Improvements in Carbureters, of which the following is a full, clear, and exact description, reference being had to the accompanying drawings, forming part of 10 this specification.

My invention relates to carbureters of the floatless type in which the admission of the fuel is directly controlled by the position of an air valve which latter is controlled in 15 its position by the vacuum produced by the suction of the engine.

One object of my invention is to provide a device which shall automatically maintain the proper quality of mixture for the engine 20 while the quantity may vary to suit the power demands made upon the engine.

Another object of my invention is the provision of means whereby the relative movement of the fuel valve may be varied 25 in its relation to the movement of the air valve, these means being capable of operation from a distant point such as the driver's seat of an automobile when the device is used in connection with such a machine.

Another object of my invention is to provide means whereby the incoming fuel is largely vaporized and entirely atomized before being mixed with the main supply of 30 air on its way to the intake of the engine.

Other objects of my invention will appear and be described throughout the specification.

In the accompanying drawings:

Figure 1 is a central sectional side elevation of a carbureter embodying my invention.

Fig. 2 is a sectional end elevation taken on the dotted line 2—2 of Fig. 1 looking in the direction of the arrows.

Fig. 3 is an enlarged sectional side elevation of the air and gas mixing valve.

The same reference characters are used to indicate identical parts in all the figures.

To show one form of construction in 50 which my invention may be embodied I have illustrated a carbureter comprising a mixing chamber A, an admission chamber B and a valve containing portion C.

Arranged within the lower portion of the 55 admission chamber B is the hollow mixing valve 1 which is supported by the hollow

stem 2, guided in the housing 3 projecting downwardly from the upper wall 4 of the admission chamber B. The upper end of the hollow stem 2 is preferably internally 60 screw threaded to receive a screw threaded stem 5 which is provided with an adjustable collar 6.

A helical spring 6' surrounds the stem 5 and bears against the collar 6 and the upper wall of the admission chamber B, the spring 6' exerting its pressure to normally hold the valve 1 approximately in the position shown in Fig. 1.

The mixing valve 1 is preferably formed 70 of the body portion 7 (see Fig. 3) and the disk 8 which may be screwed into the lower portion of the body portion thereby forming a hollow structure, the vertical wall of which is provided with a series of perforations 9 which, as clearly shown in Fig. 3 are tapered 75 so that they are larger at their exit end than they are at the end in connection with the interior of the hollow valve.

The valve 1 is preferably guided in its 80 downward travel by a series of tapered portions 10 (see Fig. 2) which are formed on the admission chamber B and extend into the mixing chamber A.

A throttle valve 11 provided with an operating arm or lever 12, is mounted in the mixing chamber A to control the quantity of mixture delivered to the engine.

The valve containing portion C comprises 85 in part the casing 13, (Fig. 1) and within the lower portion thereof, the tapered valve 14 is seated, the valve 14 controlling the flow of fuel from the fuel inlet chamber 15. A needle valve 16 is provided in the structure 90 for the purpose of regulating the maximum amount of fuel which may pass through the device.

A chamber 17 is provided above the valve 14 and a passage 18 leads from the chamber 17 to a tube 19 which latter communicates with and projects into the hollow stem 2 of the valve 1, a slot 20 being formed in the hollow stem 2 to permit the end of the tube 19 to project thereinto. The slot 20 is of sufficient length to permit the valve 1 105 and the stem 2 to move vertically a sufficient distance to accommodate the full range of the device.

An air port 21 is formed through the guide 3 and a similar port 22 is formed through 110 the hollow stem 2, these ports being so arranged with relation to each other that when

the valve 1 moves downwardly from the position shown in Fig. 1, the ports will register with one another to an extent equal to the movement of the valve 1, thereby permitting a flow of air into the hollow stem 2 and therefrom to the interior of the valve 1. The vertical alinement of the ports 21 and 22 is maintained by the tube 19, previously described, which extends through the slot 20 thereby preventing the hollow stem 2 from rotating in its guide.

10 A walking beam 23 is connected as at 24 to the upper end of the stem of the valve 14 and, through the means of a slotted opening and a pin adjacent to its end 25, is connected to the upper end of the stem 5. The walking beam 23 is provided with an elongated arcuate opening 26 which is adapted to receive a sliding block 27 the latter being 20 pivotally mounted on a movable arm 28 which is mounted upon the valve containing portion C.

25 A controlling device 29 is connected to the block 27 and provides means by which the position of this block may be shifted in the opening 26, which is formed as an arc of a circle whose center is the pivotal point of the lever 28.

30 The operation of the device is as follows: The parts as shown in Fig. 1 are all in proper position when the engine to which the carburetor may be attached is at rest, with the exception that the valve 16 is shown closed.

35 Assuming that it is desired to start the engine, the valve 16 is opened and the engine rotated either by hand or other power thereby producing a suction on the under portion of the valve 1 by the creation of a partial 40 vacuum in the chamber A. The suction on the valve 1 causes it to move downwardly, thereby compresses the spring 6' and, through the walking beam 23 and its connections lifting the valve 14 from its seat 45 and permitting a flow of fuel into the passage 18, tube 19 and hollow stem 2 and also into the hollow valve 1, the port 22 moving down into partial registration with the port 21 admits air into the hollow stem 2 and 50 this air is drawn down into the hollow valve and carries with it and vaporizes the fuel which enters the stem 2 through the tube 19.

55 The mixture thus formed passes out through the apertures 9 and between the guiding portions 10 and so into the chamber A from which it is delivered to the engine.

60 Should it be found that an insufficient amount of fuel is being admitted, the connection 29 may be operated thereby shifting the position of the block 27 with relation to the walking beam 23 whereupon the amount of fuel will be increased due to the greater amount of lift of the valve 14.

65 As the throttle 11 is operated to supply

a greater or less quantity of mixture to the engine, the vacuum within the chamber A is increased or decreased proportionately and the valve 1 moves to a position in which the tension of the spring 6' just balances 70 the amount of vacuum below the valve 1.

The tension of the spring 6' may be varied to any desired extent by the adjustable collar 6 so that the valve 1 may be caused to assume any desired position under any given 75 amount of vacuum in the chamber A.

It will be observed that the valve 1 is not provided with any seat but fits within the cylindrical lower portion of the admission chamber B in this manner permitting 80 the valve 14 to always properly seat itself to entirely stop the flow of fuel when the engine is not being operated.

The arrangement of the apertures 9 is such that should any particles of solid matter enter these apertures from the inside of the valve 1, such particles will pass entirely through the apertures 9 and not become lodged therein on account of the increasing 85 diameter of these apertures as they approach 90 the outer surface of the valve.

It will be observed that as the valve 1 moves downward within its guides 10, an increasing number of the apertures 9 is exposed to the suction produced by the engine, thereby increasing the number of jets of mixture flowing into the chamber A and assisting in the maintenance of the proper quality of the mixture as the quantity is increased, the reverse being true namely that 100 as the valve 1 rises within its guides, the number of apertures exposed to the suction produced by the engine is reduced thereby cutting off some of the jets of fuel.

Having thus fully described my invention, 105 I claim:

1. In a carburetor, the combination of a mixing chamber, an air admission chamber, a hollow valve structure mounted therein, a fuel admission valve, connections between 110 said fuel admission valve and said hollow valve whereby when the latter is operated the former is raised from its seat, a fuel duct leading from said fuel admission valve to the interior of said hollow valve structure, 115 means for admitting air into said hollow valve structure whereby when fuel is admitted thereto it will be vaporized therein by the air admitted through said means, and means for permitting the discharge of said 120 mixture from said hollow valve structure and into said mixing chamber.

2. In a carburetor, the combination of a mixing chamber, an air admission chamber, a hollow valve structure mounted therein 125 and operated by the passage of air through the device, a series of discharge ports opening from the interior of said hollow valve structure, tapered guides between which said hollow valve structure moves and for in- 130

creasing or decreasing the number of operative discharge ports, a fuel admission valve operated by said hollow valve structure, and fuel and air passages leading into said hollow valve structure whereby the mixture is formed therein and discharged into said mixing chamber.

3. In a carbureter, the combination of a mixing chamber, an air admission chamber, 10 a hollow mixing valve mounted within the device and operated by the flow of air there-through, a fuel admission valve controlled in its position by the position of said hollow mixing valve, a fuel conduit leading from 15 said admission valve to said hollow mixing valve for conveying fuel to the interior thereof, means for admitting air to the interior of said hollow mixing valve whereby the fuel and air admitted there-through are 20 mixed therein, and means for normally holding said hollow mixing valve in such position that said fuel admission valve is closed.

4. In a carbureter, the combination of a mixing chamber, an air admission chamber, 25 a hollow mixing valve movably mounted in the device and operated by the flow of air there-through, a fuel admission valve, connections between said fuel admission valve and said hollow mixing valve whereby when 30 the latter is moved by the passage of air through the device the former will be opened, a fuel conduit leading from said fuel admission valve to within said hollow mixing valve, means for admitting air through said 35 hollow mixing valve whereby when fuel is admitted there-through a mixture will be produced therein, and means for changing the proportionate lift of said fuel admission valve when said hollow mixing valve is 40 operated.

5. In a carbureter, the combination of a

mixing chamber, an air admission chamber in communication therewith, a hollow mixing valve for controlling the communication between said chambers and adapted to be operated by the passage of air from said latter to said former chambers, means for admitting fuel and air to said hollow mixing valve to form a mixture therein, means for discharging the mixture from the interior of 45 said hollow mixing valve to said mixing chamber, means controlled by the position of said hollow mixing valve for varying the effectiveness of said discharging means, means for controlling the maximum amount 50 of fuel admitted to the device, and means for shutting off a flow of fuel when the device is at rest.

6. In a carbureter, the combination of a mixing chamber, an air admission chamber 60 in communication therewith, a hollow mixing valve mounted within the structure and operated by the passage of air there-through, a fuel admission valve, connections between 65 said fuel admission valve and said hollow mixing valve whereby when the latter is operated by the passage of air through the device, the former will be opened to permit a flow of fuel, a fuel conduit leading from 70 said fuel admission valve to within said hollow mixing valve, means for admitting air through said hollow mixing valve whereby when fuel is admitted thereinto a mixture 75 will be formed therein, means for closing said fuel admission valve when said device 80 is inoperative, means for varying the proportionate amount of lift of said fuel admission valve, and means for controlling the maximum amount of fuel admitted to the device.

In testimony whereof I affix my signature.
EMIL M. KRAMER.
